UNITED STATES PATENT OFFICE.

WILLIAM R. KINNEAR, OF NEW CASTLE, PENNSYLVANIA.

PROCESS OF SEPARATING METALLIC SHEETS.

1,085,270.

Specification of Letters Patent.

Patented Jan. 27, 1914.

Application filed May 24, 1910. Serial No. 563,211.

To all whom it may concern:

Be it known that I, WILLIAM R. KINNEAR, a citizen of the United States, and resident of New Castle, in the county of Lawrence, 5 State of Pennsylvania, have invented a new and useful Process of Separating Metallic Sheets, of which the following is a specification.

My invention relates to a method of procedure whereby thin metallic sheets that have been caused to adhere, as the result of some process to which they have been subjected, may be readily and expeditiously separated or their adhesion destroyed so 15 that they may thereafter be handled or further treated.

In the manufacture of thin metallic sheets, and especially at that stage of manufacture at which the sheets are annealed in bulk, 20 the sheets generally emerge from the annealing receptacle in a condition of more or less adhesion, which necessitates forcible separation. In most cases, the degree of adhesion is such as to necessitate the application of percussion as by a heavy hammer or otherwise until separation is started at an intermediate place in the sheets after which, each sheet is grasped separately, and while the remainder of the pile is held down, 25 the sheet is stripped off. In some instances the adhesion is so great that the use of tongs is resorted to for removing the sheets.

My invention aims to provide a method by which these sheets may be taken as they 30 come from the annealing receptacle, whether in a condition of slight or extreme adhesion and to economically and expeditiously separate them without injury to the sheets.

In the accompanying drawings is illustrated 35 an apparatus suitable for carrying out the present invention and wherein—

Figure 1 shows a side elevation of the apparatus complete; Fig. 2, a top plan view thereof; Fig. 3, an elevation of part 40 of the machine partly in section; Fig. 4 is a detail view showing the feeding mechanism; Fig. 5 is a part of Fig. 3 in larger scale and Fig. 6, a detail view of the compressor plate.

50 Referring now to the details of structure of the machine, and with like characters of reference indicating corresponding parts in the several views shown, 11 designates the machine supporting means which comprises

four vertically disposed screw threaded 55 shafts suitably mounted to rotate in the base of bearing blocks, and at their upper ends they are connected by a skeleton frame 2'. The machine frame 3 is in screw threaded connection with the shafts 1 through the 60 medium of four integrally formed nuts 4 (see Fig. 1). At their upper ends each of the several shafts 1 is provided with a sprocket wheel 5 which is fixed thereon; and one of said shafts is additionally provided with a loosely mounted gear wheel 6 adapted to be coupled with said shaft through the medium of a clutch 7 that is splined thereon, and which coupling is effected through the medium of a controlling 70 lever 8 journaled in the frame 2' at 9.

The means for rotating the several shafts comprises an electric motor 10 supported upon a shelf 11 on the frame, and which motor normally drives a shaft 12 which, 75 through the medium of a clutch 13, rotates a worm 14 that is normally in mesh with the gear wheel 6 and which transmits movements thereto as will be obvious, (see Figs. 1, 2 and 4). For rotating the several shafts 80 1 in unison their sprocket wheels 5 are connected by a chain 15. Any slack in the chain is compensated for by the take-up 15'; and said chain and sprockets 5 are held against freedom of movement by the friction 85 brake 16'.

The motor 10 is designed to be constantly operated, and in order to transmit its power to cause the rotation of the shafts 1, and control the consequent downward movement 90 of the frame 3 which occurs through gravity, there is provided an automatic means operable intermittently and through the reciprocating movement of one of the sheet separating knives. This means comprises 95 an arm 16 fixed at one end to a stub shaft 17 and at its opposite end connected with one element of the clutch 13. The shaft 17 is journaled in a bearing 18 and at its lower end has a fixed short arm 19 that in turn 100 connects with a bar 20. The bar 20 is pivotally mounted to an arm 21 that is fixed on a shaft 22 within a journal bearing 23 that is mounted on the frame 2'. The shaft 22 has a second arm 24 which is also fixedly 105 mounted thereon, and which projects inwardly of the machine as shown in Fig. 2, and in which position it lies normally in

the path of a double faced cam block 25, which block is mounted upon and reciprocates with one of the sheet separating knife carriers. It will be seen from the foregoing that as the separating knife is reciprocated the cam faces of the block 25 will alternately engage with and elevate the projecting lever 24, which movement through the several members described will cause said upward movements of the arm 24 to couple and uncouple the clutch 13, thereby transmitting power from the motor to the several shafts 1, and causing the rotation of the latter for substantially brief periods, *i. e.*, the rotation of these shafts will be sufficient to regulate the downward movement of the machine a distance sufficient to compensate for the thickness of the sheet which has been removed, and properly position the separating knives for their next operation.

The means for actually separating the sheets of the pile A comprises one or two stripping knives, the present machine being shown to embody a pair of laterally and oppositely reciprocating plates or blades 26 and 27 which are mounted in carriages that slide within guideways 28 formed in the sides of the machine frame 3, (see Figs. 1 and 2). The separating blades are preferably pivotally mounted in their respective carriages, to effect which they are secured on the ledges of said carriages by means of screws and the supporting rails are in turn pivotally mounted. And to hold the blades in a parallel plane and also permit them to compensate for any irregularity in the strata of the sheets of the pile, they are held tensioned by leaf springs, which springs are adjustably secured to the plate carriages by bolts. Each of the plate supporting rails has a downwardly projecting portion adapted to coöperate with a similar member on a fixed bar, the purpose whereof will be presently explained. For reciprocating said plates there is provided a motor 29 upon a platform 30 on the frame 3. The shaft 31 of this motor is provided with a pinion 32 which, through a train gearing 33, 34, 35 and 36, operates a pair of crank arms 37. The crank arms 37 carry links 38 which connect with a stub shaft 39 carried by the knife carriage 40, and which project through their respective guideways 28, (see Fig. 1). A pair of stub shafts 39 carries rack bars 41 which mesh with pinions 42 that are loosely mounted on the shaft 43 which carries the pinion 36. The loosely rotating pinions 42 have also meshing therewith similar rack bars 44 which are carried by the guiding members 45 of the opposite blade carrying carriage, and which travel in the ways 28. For normally keeping the rack bars 41 and 44 always in mesh with the pinions 42, said rack bars are engaged and held in that relation by spools 46, as shown in Fig. 1.

From the description just given, it will be readily seen that the power of the motor transmitted through the train gearing 32—36 will, through the links 38, reciprocate the sheet separating blade 27, and that the movements of this blade will through the gearing 41, 42 and 44, cause its coöperating blade 26 to be operated simultaneously and in an opposite direction therewith.

It is devised that the topmost sheet of the pile A be gotten into position for receiving the blades 26 and 27 which effect its separation from said pile, and to accomplish this a pneumatic suction apparatus is utilized. This apparatus comprises a pump 47 (see Fig. 3), whose piston is operated through a pitman 48 that is eccentrically mounted on the shaft 49. Extending from the pump 47 are two flexible pipes 50 which lead to diametrically opposite corners of the stack of sheets A where they are connected with plungers 51. The plungers 51 are adapted to have slight vertical movement in sleeves 52 which support said plungers from the cross bar 53 of the machine frame to which they are connected by the arms 54. The means for giving movement to the plungers 51 comprises a pair of oppositely disposed lifting bars 55 which are pivotally mounted on upwardly disposed arms 56 that are in turn secured upon the cross bar 53. The free ends of the lifting bars 55 are adapted to move within guideways 57 of the plungers 51, and intermediate of their pivots and free ends said bars span the shaft 49, and at these points said shaft 49 carries cams 58 whose function is to give to the bars 55, and consequently the plungers 51, their slight upward and downward movement, as above stated.

Each of the sleeves 52 is provided with a presser foot 52' loosely mounted therein and whose upper end fits freely through a plate 53' carried by the plunger, where it is bent and rests upon said plate and by reason of which, and having the spring 54' tending to normally depress the same, said presser foot holds down that corner of the sheet immediately adjacent that portion where the suction nozzle 59 grips it. The hold down members 52' are so mounted that they continue for a brief period to depress the corners of the sheet while the plungers are lifting and thus present the second sheet. On the final upward movement of the plungers 120 the presser feet are also lifted clear of the pile.

The suction apparatus just described is timed so that the nozzle 59 on the plungers 51 are brought into contact with the topmost sheet of the pile immediately after the sheet just separated therefrom has been removed clear of the pile, and instantaneously with this contacting of the nozzles 59, suction is created by the pump 47, and instantly this

suction is created the plungers 51 are moved upwardly through the medium of the cams 58 and the lifting arms 55. Each of the nozzles 59 is connected with its respective plunger or tube 51 by a pivot pin 60 and a loose connection 61 disposed in such manner that in the upward movement of said plungers 51, the nozzles 59 assume an angular position and by doing so cause the portion of the sheet 10 directly under them to be lifted prior to the adjacent portion thereof. The reason for this provision is to have the topmost sheet of the pile instantly prepared to receive the advanced edges of the separating plates 26 and 27. As the corners of the sheets are flexed in the manner stated, their respective diametrically opposite corners are at the same instant held in close contact with the pile by means of depressing fingers 59' 20 mounted to have slight vertical movement in arms that are supported by the cross bar 53 (see Fig. 5). Said depressing members 59' are connected at their upper ends with levers 61' which are in turn pivotally supported on the machine frame and as in the instance of the lifting arms 55, the arms 61' are adapted to be elevated and depressed alternately therewith by cams that are carried by the shaft 49. 30 As the separating blades are advanced toward the pile, the blades are lifted slightly as they enter beneath the topmost sheet of the pile, and thus overcome the likelihood of the blades engaging under the second sheet 35 should the same for any reason incline to be lifted upward with the sheet to be separated. The time for this lifting of the blades 26 and 27 is so selected that immediately after the blades have entered beneath said top 40 sheet, they will drop to the level of the top of the pile.

Coöperating with the suction apparatus is a means for depressing or holding down the central portion of the sheet being separated 45 in order to insure the separation of only that sheet and also to maintain the proper symmetry of the pile. This means comprises a flexible presser plate 62 that is dependently supported from a cross head 63. The plate 50 62 is suspended from the shaft 49 by hangers 65, and for bringing said plate into contact with the pile the cross head 63 is provided with a shaft 66 that is hung from an eccentric bearing 67 also mounted on the 55 shaft 49.

The flexible plate 62 comprises four sections 62' which are coupled together by hinge joints 68 in such manner as will give them independent or separate movement 60 relative to each other.

The depressing plate has its operative mechanism so timed that it is depressed during the lifting of the corners of the sheet by the suction apparatus but will itself be 65 lifted clear of the pile at the proper move-

ment or at that instant when the separating knives 26 and 27 complete their inward movement.

As each sheet is separated after the manner described it is removed from the pile by 70 a pair of fingers 69 that are carried by the blade 27. The free ends 70 of said fingers are hooked so as to readily engage the rear edge of the sheet separated and withdraw the same with said blade 27 on its return 75 movement. When the separated sheet has been thus removed from the pile, it is brought into frictional engagement with a pair of rollers 71 that are mounted on a 80 shaft 72. The shaft 72 is journaled in a pair of blocks 72' which have vertical movement in a pair of guideways 73' upon the frame 3, the friction disks 71 are normally kept in position to engage the sheet to be removed through the medium of the springs 85 74'. The shaft 72 carrying the friction rollers is given rotary movement by a chain 73 that is driven by the shaft 49. The stripping rollers 71 thus cause the separated sheet to be removed from the machine on to 90 a suitable carrier or otherwise.

It is desired to keep the stack of sheets A in proper uniformity whereby the machine may work thereon, after once set, without necessitating any subsequent positioning or 95 adjustment of the apparatus or stack of sheets. To this end, the machine is provided with a means that centers or positions the topmost portion of the stack progressively as the frame 3 is lowered with the 100 stack. This mechanism comprises a pair of presser plates 74 that are disposed on opposite sides of the stack, as shown in Figs. 1, 2. These plates 74 are designed to come into contact with the pile A between those operations of the machine which remove the sheets. To effect this operation each of the plates 74 is carried by a head 74' that is movably supported on the bearing 75, and through links 76 is connected to the machine 105 frame at 77. Each of the blade carriers is provided with a grooved track member 78 that travels with said carriages and on each movement thereof causes the links 76 to be straightened or broken for bringing the 110 blades 74 into engagement with the pile and removing the same therefrom.

Primarily, my invention consists in foreing a relatively thin separating wedge beneath each sheet and the pile, which lies beneath it, while the sheet is maintained under conditions which will prevent buckling, until the adhesion has been overcome and the sheet may be readily removed. More specifically, the invention consists in forcing the 115 wedge beneath the sheet and the remaining sheets of the pile with its forward or wedging edge inclined to the direction of travel, whereby the wedge produces a shear effect in its action and greatly lessens the liability 120 125 130

to buckle the sheet; the sustaining force for the sheet beyond the line of separation, which prevents it buckling being preferably of such nature that a sheet is held down closely to the wedging blade so that the adhesion is overcome by pulling the sheet from the one beneath it always slightly in advance of the edge so that there is no abrasion or injury to the sheet. Preferably, this shearing effect is enhanced by having the forward wedging edge not only at an angle to the direction of travel but having it serrated or wavy in form so that the line of separation is never a straight line but there are always points or crests in the line of separation in advance of other portions of the line, which greatly facilitates the separation and reduces to a minimum the tendency to buckle.

Still more in detail, the invention consists in having the most advanced portion of the knife or wedge extend not fully to the edge of the sheet, where buckling would be favored by having the foremost portion encountering unevennesses in the edge, but said foremost portion or pilot end of the knife or wedge is slightly within the edge of the sheet and from it the knife or wedge tapers off rearwardly to the point where the edge of the sheet is encountered. This condition may exist whether the forward edge of the knife or wedge be wavy or serrated or straight, the serrations or waves on the edge are so disposed that a receding or reentrant portion occurs at the edge of the sheet on that end of the blade which travels in advance during the separation.

A further feature of the invention consists in taking advantage of certain conditions which are usually inherent in sheets that have been subjected to the annealing process as now carried out in the large mills in the country. As these sheets issue from the annealing process, the adhesion is found to occur over a greater part of the area but not extending to the corners, there being thus left certain restricted areas at the corners and extending a greater or less distance along the edges where adhesion has not developed. This feature of my invention consists in utilizing these portions of the sheets for initial separation effected by mechanical means for the purpose of admitting the separating wedge and permitting it to start its operation. But even this initial separation, is carried on under conditions in which buckling of the sheet or bending up of the corner is prevented, for here as well as in the main separation process, the portion of the sheet beyond the part, which is immediately effected by the separating means, is held down. This simultaneous lifting of a portion of the sheet (preferably the corner) somewhat within the extreme edge and the holding down of the sheet at the extreme edge produces a welling up or bowing of the sheet

at a point at which the pilot end of the knife enters and thus the process of separation is initiated under conditions which insure the avoidance of buckling until complete separation has taken place.

After the sheet is free, it is displaced edgewise by any suitable means.

In practice, the separation is facilitated both as to time and certainty of operation by duplicating the knife or wedge on opposite sides of the pile to be attacked, the effect being best produced by having the separating edges parallel so that the pilot ends are near opposite lateral edges of the plates and having the knives move in opposite directions so that they come together at an intermediate position when the separation will be completed after which the knives recede to a position where they are ready to attack another sheet and separate it as before.

The separating knife or wedge is thin enough to flex considerably during the separating stroke and thereby adapt it to conform to any buckled or uneven condition in the surface of the pile.

The means for sustaining the sheet being separated against the buckling is preferably in the form of plate or plates, which, during the separating stroke, is spaced above the pile a distance corresponding substantially to the thickness of the knife plus the thickness of the sheet that is being lifted. Any other means, however, might be employed for this purpose so long as it involves the principle of imposing pressure over a sufficiently large area of the separated sheet, commencing with a point relatively near the line of separation, to prevent buckling at that line or prevent the knife from raising above the stack sufficiently to bend the sheet being separated and form a crease.

The means for causing the initial separation first begins to act on the sheet while it lies symmetrically on the pile and these means are, therefore, preferably employed for continuing their hold upon the sheets until not only separation but engagement of the removing means has taken place in order to prevent a sheet becoming displaced laterally where adhesion is only slight and is overcome prior to the completion of the stroke of the knives.

Having thus described my invention, what I claim as new therein and desire to secure by Letters Patent is:—

1. The process of separating adhering metallic sheets, which consists in forcing a wedging device between the adjoining surfaces of the sheets to be separated, while the sheet is being sustained to prevent lateral displacement thereof.

2. The process of separating adhering metallic sheets, which consists in forcing between the adjoining surfaces of the sheets to be separated a wedging means, and simul-

- taneously holding down the separated portion of the sheet in a plane substantially parallel with the original position of the sheet.
- 5 3. The process of separating adhering metallic sheets, which consists in raising a portion of the top sheet and forcing between the adjoining surfaces of the sheets to be separated a wedging means, and simultaneously holding down the separated portion of the sheet in a plane substantially parallel with the original position of the sheet, and closely lying upon the wedging means.
- 10 4. The process of separating adhering metallic sheets, which consists in forcing between the surface of the sheet to be separated and that to which it adheres, a wedging device having its forward edge presented at an acute angle to the direction in which it travels, while the sheet to be separated is being held from lateral displacement, said holding being continued until the separation has been completed.
- 15 5. The process of separating adhering metallic sheets which consists in raising a portion of the uppermost sheet and forcing a wedge between the sheet to be separated and the one to which it adheres, and causing the separating action to occur in an irregular line across the sheet, the advance point thereof lying within the side edges of the sheet.
- 20 6. The process of separating adhering metallic sheets which consists in raising a portion of the uppermost sheet and forcing a wedge between the sheet to be separated and the one to which it adheres, and causing the initial separating action to occur at a point within the side edges of the sheet, and continuing the separating action in an irregular line across the sheet with the advance point thereof lying within the side edges of the sheet.
- 25 7. The process of separating adhering metallic sheets, which consists in forcing between the sheet to be separated and the one to which it adheres, two wedging devices attacking the sheet from opposite edges with their wedging edges disposed at an angle to the direction of their travel, and parallel to each other, whereby their pilot ends are located near opposite lateral edges of the sheet and the wedges are adapted to meet to complete the separation.
- 30 8. The process of separating adhering metallic sheets, which consists in preliminarily raising a portion of the sheet within the edge while holding down the corner of the sheet beyond said raised portion and then entering a separating wedge in the opening thus presented, while the sheet to be separated is being held from lateral displacement.
- 35 9. The process of separating adhering metallic sheets, which consists in preliminarily raising a portion of the sheet within the edge while holding down the corner of the sheet beyond said raised portion and then entering a separating wedge in the opening thus presented, and forcing it beneath the sheet to be separated with its edge extending at an angle to the direction in which the wedge is moved, while the sheet to be separated is being held from lateral displacement.
- 40 10. The process of separating adhering metallic sheets, which consists in preliminarily raising a portion of the sheet within the edge while holding down the corner of the sheet beyond said raised portion and then entering a separating wedge in the opening thus presented, and forcing it beneath the sheet to be separated with its edge extending at an angle to the direction in which the wedge is moved, and the portion of the separating wedge extending toward the held down edge of the sheet extending backwardly so that it encounters and raises said held down portion after the pilot end of the separating wedge has entered beneath the sheets.
- 45 11. The process of separating adhering metallic sheets, which consists in preliminarily raising a portion of the sheet within the edge while holding down the corner of the sheet beyond said raised portion and then entering a separating wedge in the opening thus presented, and causing the raising means to continue its holding influence on the sheet until separation is completed and thereby prevent lateral displacement of the sheet.

The foregoing specification signed at New York, N. Y., this 17th day of May, 1910.

WILLIAM R. KINNEAR.

In presence of two witnesses:

M. L. SULLIVAN,
I. M. BLANCHFIELD.
